DESIGN FOR A COMPACT CASE

Harry Bayar, New York, N. Y.

Application November 4, 1935, Serial No. 59,379

Term of patent 3½ years

To all whom it may concern:

Be it known that I, Harry Bayar, a citizen of the United States, residing at 64 West 52nd Street, in the county of New York, State and city of New York, have invented a new, original, and ornamental Design for Compact Cases, of which the following is a specification, reference being had to the accompanying drawing, forming part thereof.

In the drawing:

Figure 1 is a front perspective view of a compact case showing my new design in closed position.

Figure 2 is a front perspective view thereof in

opened position, showing the interior compartments closed with the chain and key elements indicated in Fig. 1 missing but its presence here should be assumed, and

Figure 3 is a front perspective view thereof in opened position with the interior compartments opened with the chain and key elements indicated in Fig. 1 missing but its presence here should be assumed.

I claim:

The ornamental design for a compact case substantially, as shown and described.

HARRY BAYAR.
